UNITED STATES PATENT OFFICE.

BERTHA CLARK, OF BROOKLYN, NEW YORK.

SHOE-HANGER.

1,310,281.

Specification of Letters Patent. Patented July 15, 1919.

Application filed February 1, 1919. Serial No 274,422.

To all whom it may concern:

Be it known that I, BERTHA CLARK, a citizen of the United States, and a resident of the city of New York, borough of Brooklyn, 5 in the county of Kings and State of New York, have invented a new and Improved Shoe-Hanger, of which the following is a full, clear, and exact description.

The invention relates to apparel apparatus, and its object is to provide a new and improved shoe hanger more especially designed for home use and adapted to be mounted in closets or other places to compactly support a pair of shoes, slippers or 15 similar footwear. Another object is to hold the toe portions of the shoes or other footwear in stretched condition thus maintaining the shape of the footwear and preventing cracking of the uppers. Another 20 object is to permit of conveniently placing the shoes in position on the shoe hanger or removing them therefrom whenever it is desired to use the shoes.

With these and other objects in view, the 25 invention consists of certain novel features of construction as hereinafter shown and described and then specifically pointed out in the claims.

A practical embodiment of the invention 30 is represented in the accompanying drawings forming a part of this specification, in which similar characters of reference indicate corresponding parts in all the views.

Figure 1 is a front elevation of the shoe 35 hanger with a pair of shoes in position thereon, one of the shoes being shown broken out;

Fig. 2 is a side elevation of the shoe 40 hanger;

Fig. 3 is a perspective view of a modified form of the shoe hanger; and

Fig. 4 is a similar view of another modified form of the shoe hanger.

The frame 10 of the shoe hanger for supporting a pair of shoes 11 is preferably 45 made of a piece of wire doubled up to provide an upright shank or stem 12 formed at its upper end into a hook 13 for engagement with a support 14 in the form of a rod 50 attached by suitable brackets (not shown) to the wall of a closet or the like in which shoes are kept while not in use. The wire portion forming the hook 13 is arranged to provide a loop adapted to be engaged with a 55 nail or other support for supporting a shoe

hanger instead of supporting it from the rod 14, as above explained. The shank or stem 12 is provided at its lower end with forwardly extending arms 20 slightly curved upward and terminating in return 60 bends 21 extending in opposite directions and terminating in angular portions 22 on the lower ends of shoe-holding members 23 extending upwardly and terminating in toe-stretching heads 24 adapted to fit into the 65 toe portions of the shoes 11. As illustrated in Figs. 1 and 2, each of the heads 24 is made in two parts and the corresponding shoe holding member 23 is likewise made in two parts or arms 25, 26 of which the arm 70 25 forms part of the wire of which the frame is made while the arm 26 is attached at its lower end to the lower end of the arm 25. The arms 25 and 26 diverge to hold the sections of the head 24 spread apart to 75 stretch the toe portion of the corresponding shoe 11, as will be readily understood by reference to Fig. 1. The arms 25 and 26 are adapted to be moved toward or from each other by an S hook 27 engaging the 80 arms. Thus by moving the S hook 27 downward the arms 25, 26 and the head sections are spread apart, and by moving the S hook upward the arms 25 and 26 and their head sections are moved toward each other. Thus 85 by the arrangement described the toe portion of the shoe can be stretched more or less as desired by the user. When placing a shoe 11 in position on the shoe supporting member 23 the head 24 engages the toe portion of the shoe while the lower end of the shank 23 rests against the inner surface of the sole of the shoe as indicated in Fig. 2. It will be noticed that by the arrangement 90 described the shoes 11 of a pair are properly supported side by side on the shoe hanger and the toes are kept in stretched condition 95 thus maintaining the shape of the shoes and preventing cracking of the uppers.

In the modified form shown in Fig. 3, the 100 toe stretching heads 24 form integral parts of the shanks 23 instead of being made of wooden sections, as shown in Figs. 1 and 2. In this case the arms 26 and the S hooks 27 are omitted. In order to hold the doubled-up wires forming the shank 12 close together one of the wires is preferably twisted around the other wire, as indicated at 28 in Figs. 1, 2 and 3, and bands 29 may be fastened around the two wires forming the 110

shank 12 to hold the said wires together with a view to stiffen the shank, as indicated in Fig. 3.

In the modified form shown in Fig. 4, the shank 12, instead of terminating in a combination hook and loop 13, terminates in a screw 30 adapted to be screwed into a wall or other suitable support. The shank 12 in this case is preferably disposed horizontally and its forwardly extending and upwardly curved portion 20 is engaged with the return bends 21 terminating in the portions 22 of the upright shanks 23, the upper ends of which are formed into heads 24 for engagement with the toes of the pair of shoes to be supported.

The shoe hanger shown and described is very simple and durable in construction and can be readily attached to a suitable support. A pair of low or high shoes or a pair of slippers or similar footwear can be readily placed in position on the hanger to support the shoes side by side without taking up much space. It will also be noticed that the shoes are supported with the toes upward and the toes are stretched at the sides by the heads 24. The bends 21 and the adjusting portions of the arms 20 and 22 projecting out of the shoes provide a hook for supporting other articles.

Having thus described my invention, I claim as new and desire to secure by Letters Patent:—

1. A shoe hanger for supporting a pair of shoes, comprising upright shoe holding members spaced apart and adapted to pass separately into the shoes to support the latter side by side in an upright position and with the toes upward, the lower ends of the supporting arms having forwardly extending portions extending out of the shoes, and a shank intermediate the said shoe supporting member and connected at one end with the ends of the said extended portions of the arms, the other end of the said shank having means for engagement with a support.

2. A shoe hanger for supporting a pair of shoes, comprising upright shoe holding members spaced apart and adapted to pass separately into the shoes to support the latter side by side in an upright position and with the toes upward, the lower ends of the supporting arms having forwardly extending portions extending out of the shoes, the upper ends of the said shoe supporting members having two stretching heads adapted to fit into the toes of the shoes, and a shank intermediate the said shoe supporting member and connected at one end with the ends of the said extended portions of the arms, the other end of the said shank having means for engagement with a support.

3. A shoe hanger for supporting a pair of shoes, comprising upright shoe supporting

members spaced apart and adapted to pass separately into the shoes to support the latter side by side in upright position with the toes upward, each shoe supporting member having diverging spring arms terminating in toe stretching heads fitting into the toes of the corresponding shoe, the lower ends of the said shoe supporting members having forwardly extending angular portions extending out of the shoes, and a shank intermediate the said shoe holding members and connected at one end with the outer ends of the said angular portions of the shoe supporting members, the other end of the said shank having means for attaching the shoe hanger to a support.

4. A shoe hanger for supporting a pair of shoes, comprising upright shoe-supporting members spaced apart and adapted to pass separately into the shoes to support the latter side by side in upright position with the toes upward, each shoe supporting member having diverging spring arms terminating in toe stretching heads fitting into the toe of the corresponding shoe, the lower ends of the said shoe supporting members having forwardly extending angular portions extending out of the shoes, means for moving the said spring arms of a shoe supporting member toward or from each other, and a shank intermediate the said shoe holding members and connected at one end with the outer ends of the said angular portions of the shoe supporting members, the other end of the said shank having means for attaching the shoe hanger to a support.

5. A shoe hanger for supporting a pair of shoes, comprising an upright shank provided at its upper end with means for suspending the shank from a suitable support, the lower end of the shank having a forwardly extending angular portion, shoe holding members having upright portions, and forwardly extending angular portions connected with the forward end of the said angular shank portion, and toe stretching heads on the upper ends of the said upright portions of the shoe holding members and adapted to fit into the toes of the shoes to be supported.

6. A shoe hanger for supporting a pair of shoes, comprising an upright shank provided at its upper end with means for suspending the shank from a suitable support, the lower end of the shank having a forwardly extending angular portion, shoe holding members having upright portions and forwardly extending angular portions connected with the forward end of the said angular shank portion, and toe stretching heads on the upper ends of the said upright portions of the shoe holding members and adapted to fit into the toes of the shoes to be supported, the lower ends of the said upright portions of the shoe holding mem-

bers resting against the inner faces of the soles of the shoes.

7. A shoe hanger for supporting a pair of shoes side by side and made of a single piece of wire doubled up to form an upright shank provided at the doubled up end with a loop and a hook, the shank having a lower forwardly extending portion terminating in return bends, and upright shoe holding members terminating in lower forwardly extending portions integrally connected with the said return bends.

8. A shoe hanger for supporting a pair of shoes side by side and made of a single piece of wire doubled up to form an upright shank 15 provided at the doubled up end with a loop and a hook, the shank having a lower forwardly extending portion terminating in return bends, upright shoe holding members terminating in lower forwardly extending 20 portions integrally connected with the said return bends, and toe stretching heads on the upper ends of the said shoe holding members.

BERTHA CLARK.
